ATTORNEY.

United States Patent Office.

WILLIAM S. TOOKER, OF KINGSBOROUGH, NEW YORK, ASSIGNOR TO HIMSELF AND ELLIOT THOMAS, OF SAME PLACE.

Design No. 4,716, dated March 14, 1871.

DESIGN FOR BACKS OF MITTENS.

The Schedule referred to in these Letters Patent and making part of the same.

To all whom it may concern:

Be it known that I, WILLIAM S. TOOKER, of Kingsborough, in the county of Fulton and State of New York, have invented a new and original Design for Backs of Mittens; and I do hereby declare that the following is a full, clear, and exact description thereof, which will enable others skilled in the art to make and use the same, reference being had to the accompanying drawing forming part of this specification.

This invention relates to a design for the outside of a mitten as contradistinguished from the palm or inside thereof.

The drawing represents a view of the piece constituting the back of a mitten.

a is the back of the thumb, while *b* is the seam, which unites the under piece to the upper piece of the thumb, and *c* the seam which unites the palm and the back pieces of the mitten.

Having thus described all that is necessary to a full understanding of my invention,

What I esteem to be new, and desire to protect by Letters Patent, is—

The design for the back piece of a mitten, substantially as described and illustrated.

WILLIAM S. TOOKER.
